UNITED STATES PATENT OFFICE.

CHARLES C. BILLINGS, OF BOSTON, MASSACHUSETTS.

MACHINE FOR COLD-DRAWING RODS, &c.

SPECIFICATION forming part of Letters Patent No. 295,898, dated April 1, 1884.

Application filed September 3, 1883. (No model.)

To all whom it may concern:

Be it known that I, CHARLES C. BILLINGS, of Boston, county of Suffolk and State of Massachusetts, have invented an Improvement in 5 Machines for Cold-Drawing Rods, Shafting, &c., of which the following description, in connection with the accompanying drawings, is a specification, like letters on the drawings representing like parts.

10 This invention relates to that class of machines represented in United States Patent No. 130,465, and has for its object a novel construction of die and means for holding and adjusting the same, whereby the rod or shaft may be drawn straight, and also to improvements in the clutch for holding the rod, as will be hereinafter described and pointed out in the claims.

15 Figure 1 is a longitudinal section of a sufficient portion of a machine embodying my invention to enable the same to be understood. Fig. 2 is a section of Fig. 1 on the dotted line $x x$. Fig. 3 is a section of Fig. 2 on the dotted line $x^2 x^2$; and Fig. 3^a is a section of Fig. 1 on the dotted line $x^3 x^3$, to show the end of the head 25 and jaws therein, forming the clutch. Fig. 4 represents the knife-edge bearings removed; Figs. 5 and 6, modifications to be referred to.

20 My improved machine contains a cylinder, A, on which is fitted a piston, B, having a rod, C, which at its outer end is provided with a clutch, D, composed of a block of steel open at one side at a' , to gain access to the clutch interior, and at one end a^2 , and chambered centrally for the reception of two toothed jaws $a a$, shown as wedge-shaped at their backs, to bear 35 against the correspondingly-wedge-shaped seats in the said chambered block.

30 Referring to Fig. 3^a, it will be seen that the head D at its front end is solid, except at its center, where it is mortised to receive the jaws $a a$, so that strain upon the latter when drawing a rod cannot expand the head, as would be the case if the end of the head were split from its outer side to the jaw-receiving opening. 40 The jaws, having been inserted into the head, have the end of the rod R to be drawn placed between their toothed faces, and the jaws are then drawn or forced along the inclined seats of the head, toward its open end, until the toothed 45 surfaces of the jaws bite the rod, and thereafter as the clutch is drawn in the direction of

the arrow on it in Fig. 1 the jaws close upon and hold the said rod sufficiently tight to draw it through the die e, to be described. The piston B is operated by water or other suitable fluid. The clutch-head in practice will be provided with grooves to run on ways of the frame E, as does the cross-head of an engine. The die e, a loose block of steel perforated centrally and made cone-shaped externally, is fitted into 50 the conical interior of the die-seat f. This die-seat (shown in Figs. 1 to 3) has an outer rim, f, which is pivoted by center screws, f^2 , extending through the seat-holder g, which latter is pivoted to the frame F by center screws, g^2 , 55 located at right angles to the center screw, f^2 , of the die-seat, so that the frame F and die-seat form a gimbal or universally-pivoted bed or holder for the die. The frame-work F has steel knife-edge bearings i, about or on which 60 the seat-holder g rests and is made movable. The die-seat f is provided with steel knife-edge bearings h, which rest against the flat side of the seat-holder g, constituting points on or about which the said seat f turns with relation 65 to the said holder. The flanged or outer end of the die-seat is acted upon at preferably four points, ninety degrees apart, by adjusting-screws m, which may be turned in or out each 70 one more or less, and thereby turn the die-seat 75 upon the holder about the points h, and the holder on the frame F about the points i, the said adjusting-screws enabling the operator of the machine to tip the die-rest and place the die e in exactly the position desired to enable 80 the rod R, being drawn through its tapered central opening, to be placed in exactly such position with relation to the movement of the piston and clutch, or to force the die to occupy 85 and maintain a position directly in line with 90 the center of the clutch, which thus enables the rod to be drawn straight. These bearings or points h i are exactly in line with the supporting center screws, $f^2 g^2$, before referred to.

95 As a modification I may support the die-seat on a holder, o, which is fixed with relation to the frame F; but in such modification I shall bevel the wall of the die-seat more than shown in Figs. 1 and 3, and support the said beveled portion directly upon bearings or surfaces, shown as rollers and marked n, the same 100 adjusting-screws m being used to adjust and

position the die-seat and its die *e* with relation to the draft of the clutch, as described, I employing with the modified seat described a clutch-jaw, as shown and described with relation to Figs. 1 to 3. In the patent referred to the die was self-centering, and there is no provision whatever to adjust the same to the line of draft or to avoid drawing the rods or bars crooked.

10 The machine, with a die of proper shape, is adapted to cold-draw and compress solid or hollow rods or articles either round or square, or of other usual shapes.

I do not limit my invention to the use of the 15 exact clutch shown, as I may employ any usual clutch or device to grasp the rod; or it may be a tube.

I do not claim a two-part adjustable die placed in a fixed seat and adjustable only in 20 a radial direction with relation to the axis of the rod being drawn, as such is described in United States Patent No. 168,975.

I claim—

1. In a machine for cold-drawing rods, &c., 25 a clutch to hold the rod or article to be drawn, a die, a movable or tipping die-seat to receive and hold the said die, and bearing-points to support the die-seat externally, and permit it with its inclosed die to be adjusted to tip or 30 turn the die-seat and place the center of the

die in proper relation to the line of draft of the clutch, combined with means, substantially as described, to act upon the die-seat at that side of it opposite the side acted upon by the said bearing-points, to thereby adjust the said die-seat, and with it its inclosed die, to operate as and for the purposes set forth. 35

2. The movable clutch, the die *e*, die-seat, and holder, and center screws and bearings or points, *h i*, combined with means, substantially 40 as described, to adjust the die-seat and die-holder with relation to the frame of the machine and the draft of the clutch, substantially as described.

3. The piston and its piston-rod, combined 45 with the herein-described clutch consisting of the hollow head open at *a'* and *a''*, the walls surrounding the opening *a'*, converging from within outward and affording beveled or inclined seats, and jaws having inclined backs 50 to fit in said seats, substantially as and for the purpose set forth.

In testimony whereof I have signed my name to this specification in the presence of two subscribing witnesses.

CHAS. C. BILLINGS.
